CLAIM

The ornamental design for a stove, as shown and described.

DESCRIPTION

FIG. 1 is a perspective view of a stove, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of FIG. 1; and,

FIG. 10 is an enlarged view of FIG. 2.

The broken line showing of the stove is for the purpose of illustrating article and forms no part of the claimed design.

1 Claim, 10 Drawing Sheets
